METHOD OF AND SYSTEM FOR TELEPHONIC TRANSMISSION.

Application filed December 26, 1925. Serial No. 77,777.

This invention relates to a method of and system for telephonic transmission and aims more particularly to provide a secret method of and system for telephonic transmission, 5 applicable to radio telephony.

In accordance with an important feature of the invention, the frequency order of speech or other telephonic waves is inverted, so that the telephonic waves of lower frequencies are 10 represented by waves of relatively high frequencies, whereas the telephonic waves of higher frequencies are converted into waves of lower frequencies than the above-mentioned relatively high frequencies, and the 15 inverted, telephonic waves are caused to modulate a carrier wave which is transmitted in sending a message.

A further feature of the invention contemplates inverting the frequency order of 20 the telephonic waves substantially within their own frequency range. One way in which this may be done is by causing them to modulate current of a frequency near the higher frequency of the telephonic waves.

25 In receiving a message sent in accordance with the invention currents are produced corresponding in frequencies with the inverted, telephonic waves, and these currents may be caused to modulate current of the same frequency as that modulated by the telephonic waves at the transmitter, thereby producing 30 energy of the same frequencies and frequency order as the telephonic waves. This energy may then be employed to operate a suitable indicator.

In order to enable the inverted, telephonic waves to be obtained without intermingling of the original, telephonic waves with them, the inversion of the telephonic waves within 40 a desired frequency range is, preferably, and in accordance with a still further feature of the invention, effected in a plurality of steps so constituted as to enable the inverted, telephonic waves to be readily separated by known filtering devices from the original waves. A preferred method of so performing the inversion of the telephonic waves is to convert them in inverted frequency order into a higher frequency range and then to step 45 them down to the desired frequency range without affecting their inverted character. This may be done by causing them to modulate current of a super-audible frequency and

55 by then modulating the lower side band resulting from such modulation by current of a super-audible frequency lower than the first-mentioned, super-audible frequency and differing therefrom by an amount determined by the desired frequency values of the inverted, telephonic waves.

60 The invention also provides a receiver of energy modulated by inverted, telephonic waves including means for producing from the received energy currents having the frequency characteristics of the inverted, telephonic waves, means for converting said currents into a higher frequency range and simultaneously inverting them to obtain currents of the frequency order of the original, telephonic waves, and means for stepping 65 down the frequency values of the last-mentioned currents to a desired frequency range which may be that of the original, telephonic waves. These means may comprise modulators which may conveniently be of the vacuum 70 tube type and are preferably provided with means for supplying them with currents of different, super-audible frequencies respectively differing from each other by an amount necessary to transpose the inverted, telephonic 75 waves into energy of the frequencies of the original, telephonic waves.

The invention further contemplates the provision of filters wherever required to suppress undesired side bands resulting from 80 modulation or to prevent current supplied to a modulator from intermingling with currents resulting from modulation.

85 Still other objects and features of the invention will be apparent as the description 90 proceeds and will be pointed out in the appended claims.

In the drawings,

Fig. 1 is a diagrammatic representation of a transmitting arrangement embodying the 95 invention;

Fig. 2 is a diagrammatic representation of a receiving arrangement also embodying the invention; and

Figs. 3 and 4 show different embodiments 100 of the transmitting and receiving arrangements respectively.

The embodiment of the invention illustrated in Fig. 1 of the drawings comprises a circuit 10 including a telephone transmitter 105 12 and a battery 13. Coupled with the circuit

10 is a vacuum tube modulator 14 of the well-known push-pull type which suppresses the unmodulated carrier component. The modulator 14 includes two, three-electrode vacuum tubes 16 and 18 and a source 20 of current to be modulated by the telephonic waves produced in the circuit 10.

10 The modulation of current from the source 20 by the telephonic waves results in the production of upper and lower side bands, and in order to suppress one of these side bands, preferably the upper band, a band filter 22 is coupled with the output side of the modulator 14. The filter 22 is also coupled to the input

15 side of a combined modulator and carrier wave generator 24-26 from which energy is radiated into the ether by an antenna 28 which may be tuned to the frequency of the waves produced by the generator 26.

20 If it be assumed that the frequencies of the telephonic waves vary within limits of 200 to 3,000 cycles per second, which may be substantially true of speech frequencies, then the frequency of the current produced

25 at the source 20 of the modulator 14 is preferably about 3,000 cycles per second; that is, the frequency of the current at the source 20 preferably lies near the higher frequencies of the telephonic waves.

30 The modulator 14, in the case assumed, produces an upper side band composed of currents of frequencies between 3,200 and 6,000 cycles per second in which the frequency order of the telephonic waves is not

35 inverted and a lower side band composed of currents of frequencies between zero and 2,800 cycles per second respectively in which the frequency order of the telephonic waves is inverted. The filter 22 suppresses

40 currents belonging to the upper side band and impresses upon the modulator-generator 24-26 inverted, telephonic waves varying in frequency between zero and 2,800 cycles. It will appear clearly from the foregoing

45 that the frequency values of the inverted, telephonic waves depend upon the frequency of the current supplied from the source 20. For example, if the frequency of the current at the source 20 was 4,000 cycles per sec-

50 ond instead of 3,000, the frequency values of the inverted, telephonic waves would lie within limits of 1,000 cycles and 3,800 cycles respectively. It will further be understood

55 that the provision of current of a frequency of 3,000 cycles per second at the source 20 of the modulator 14 causes the inverted, telephonic waves to lie within substantially the same frequency range as do the original, telephonic waves, or, in other words, the

60 range of frequency values of the inverted, telephonic waves is to a considerable degree the same as that of the original, telephonic waves.

The arrangement shown in Fig. 2 for receiving energy, modulated by the inverted,

telephonic waves and radiated by the antenna 28, comprises an antenna 30 connected with the input side of a vacuum tube detector 32. The output side of the detector 32 is coupled with a push-pull modulator 34 70 similar to the modulator 14 of Fig. 1 and including two, three-electrode vacuum tubes 36 and 38 and a source 40 of current of the same frequency as that of the source 20 of the modulator 14, namely, in the case assumed, 3,000 cycles. The output side of the modulator 34 is coupled with a band filter 42 connected with a suitable indicator 44 which may, as shown, be in the form of a telephone receiver. 80

The detector 32 produces from the energy induced in the antenna 30 currents of frequencies corresponding with the frequencies of the inverted, telephonic waves impressed upon the modulator-generator 24-26 of 85 Fig. 1. The frequencies of such currents, in the case assumed, would lie within limits of zero and 2,800 cycles per second respectively. These currents in the device 34 modulate

90 current of a frequency of 3,000 cycles per second provided from the source 40, thereby producing upper and lower side bands, the latter of which varies in frequency between limits of 200 and 3,000 cycles per second in the same manner as do the original, telephonic waves. The currents in the lower side band are, moreover, of the same frequency order as the original, telephonic waves. The filter 42 suppresses the upper side band resulting from the action of the modulator 34 and passes the lower side band of frequencies from 200 cycles to 3,000 cycles so that they may operate the telephone receiver 44. 100

The inversion of the telephonic waves before they are impressed upon the modulator-generator 24-26 of Fig. 1 renders the message unintelligible to one employing an ordinary type of receiver. However, a message transmitted from an arrangement such as is shown in Fig. 1 may not only be received by the arrangement shown in Fig. 2, but may be of as good quality as though no effort had been made to send it secretly. 110

If it is not desired that the telephonic 115 message received at the indicator 44 shall be of exactly the same pitch as that impressed upon the transmitter 12 of Fig. 1, the current at the source 40 of the modulator 34 may not be of precisely the same frequency as that at the source 20 of the modulator 14. A difference in frequency of the currents at these sources will change the pitch of the message to a corresponding degree, but if the difference is not too great, 120 will not prevent the message from being intelligibly received.

In the modified form of transmitter shown in Fig. 3, the circuit 50 including the telephone transmitter, the band filter 52

which passes the inverted, telephonic waves and suppresses currents of other undesired frequencies, the modulator-generator 54—56 and the antenna 58 correspond in function and construction with the parts 10, 22, 24—26 and 28 respectively of Fig. 1. In the embodiment of the invention shown in Fig. 3, however, the inversion of the telephonic waves is accomplished in two steps so constituted as to enable the inverted, telephonic waves to be readily obtained free from undesired currents. As shown, the means for inverting the telephonic waves includes a modulator 60 comprising two, three-electrode vacuum tubes 62 and 64. The modulator 60 is similar to the modulator 14 of Fig. 1 except that it is provided with a source 66 of current of different frequency. The frequency of the current at the source 66 may, for example, be 33,000 cycles per second.

The modulator 60 is connected with a filter 68 also connected with a second modulator 70 which may as shown comprise a single three-electrode vacuum tube and a source 72 of current of a frequency differing from the frequency of the current at the source 66 by an amount depending upon the desired value of the frequency range of the inverted, telephonic waves. The modulator 70 comprises windings 74 and 76 in its grid-filament circuit coupled respectively with the filter 68 and the source of current 72.

In the operation of the transmitting arrangement shown in Fig. 3, the telephonic waves produced in the circuit 50 are caused to modulate current of the frequency of the source 66, for example, 33,000 cycles per second. The modulator 60 produces upper and lower side bands of such frequency and itself suppresses the unmodulated current of 33,000 cycles. The band filter 68 suppresses the upper side band and passes the lower side band, the frequencies of which, in the case assumed, vary between 30,000 cycles and 32,800 cycles per second. Currents of the last-mentioned frequencies are then impressed upon the modulator 70 along with currents supplied at the source 72 of a frequency, for example, of 30,000 cycles per second. Since the modulator 70, as shown, is not of the type which suppresses the unmodulated carrier component, the output circuit of the modulator 70 will contain currents of a frequency of 30,000 cycles per second, currents of frequencies of 30,000 to 32,800 cycles per second, and upper and lower side bands of such frequencies.

From the foregoing, it will be understood that the modulator 60 acts to invert and step up the frequencies of the telephonic waves, the band filter 68 passes the inverted and stepped up waves and suppresses the non-inverted waves of the upper side band, the

modulator 70 steps down the frequency of the inverted, telephonic waves without affecting their inverted character and the band filter 53 suppresses all currents other than the desired, inverted, telephonic waves.

The use of current of a super-audible frequency, such as 33,000 cycles per second, at the modulator 60 causes the inverted waves passed by the band filter 68 to lie within a range of frequencies remote from that of the telephonic waves so that the desired, inverted waves can be readily separated from the telephonic waves by known filters. Moreover, current of the carrier frequency is suppressed due to the construction of the modulator 60 and does not pass to the filter 68. Accordingly, such filter impresses upon the modulator 70 the inverted, stepped-up, telephonic waves unmixed with any undesired currents. The currents supplied to the modulator 70 are all of frequencies so far different from the frequencies of the lower side band which the band filter 52 is designed to pass to the modulator-generator 54—56 that the inverted, telephonic waves are readily obtained free from other currents which may result from the action of the modulator 70.

By providing currents of frequencies of 33,000 cycles per second and 30,000 cycles per second at the source 66 of the modulator 60 and the source 72 of the modulator 70 respectively, the inverted, telephonic waves impressed upon the modulator-generator 54—56 are caused to be of the same range 100 of frequencies as those obtained by inversion of the telephonic waves in Fig. 1, namely, in the case assumed, zero to 2,800 cycles per second. The reason for this is that the frequencies 33,000 and 30,000 cycles differ by an 105 amount equal to the frequency of the current provided at the source 20 of Fig. 1, namely, 3,000 cycles. That the frequency range of the inverted, telephonic waves supplied by the band filter 52 in Fig. 3 is governed by the difference in frequencies of the currents at the sources 66 and 72 can readily be seen, if it is assumed that the frequency of the current at the source 66 remains at 33,000 cycles and current of the 110 frequency of 29,000 cycles per second is provided at the source 72 in which case the inverted, telephonic waves in the lower side band produced by the modulator 70 will range in frequency between 1,000 cycles and 3,800 cycles per second, and if it is then assumed that the frequency of the current at the source 66 is 32,000 cycles, whereas current of 29,000 cycles is provided at the 115 source 72, in which case the frequency range of the lower side band produced by the modulator 70 will again be between zero and 2,800 cycles.

The receiving arrangement shown in Fig. 4 of the drawings is designed to receive en- 130

ergy modulated by inverted, telephonic waves with the same freedom from intermingling of undesired currents with currents of desired frequencies as is obtained in the transmitting arrangement of Fig. 3. The receiving arrangement illustrated in Fig. 4 comprises an antenna 80 connected with the input side of a detector 82, the output side of which is connected with a modulator 84 including two, three-electrode vacuum tubes 86 and 88 and a source 90 of current of super-audible frequency, for example, 33,000 cycles per second. The modulator 84 is connected with a band filter 92 the output side of which is in turn coupled with a modulator 93. The input side of the modulator 93 comprises windings 94 and 96 coupled respectively with the band filter 92 and a source 98 of current of super-audible frequency, for example, 33,000 cycles per second. Connected with the output side of the modulator 93 is a band filter 100 which passes current to the circuit of a telephone receiver 102.

25 The detector 82 produces from the energy induced in the antenna 80 current of frequencies corresponding with those of the inverted, telephonic waves employed to modulate the transmitted carrier wave.

30 These currents in the case assumed vary through a frequency range of zero to 2,800 cycles per second and are caused to modulate current of 33,000 cycles provided from the source 90. The modulator 84 itself suppresses unmodulated current of the frequency of 33,000 cycles, and the upper side band produced by the modulator is suppressed by the filter 92 which impresses upon the modulator 93 currents belonging to the lower side band produced by the modulator 84 and varying in frequencies from 30,200 cycles to 33,000 cycles per second. The modulator 93 produces from the lower side band of the modulator 84 currents ranging in frequencies from 200 cycles to 3,000 cycles per second. It will be noted that these currents are of the same frequencies as those set up in the telephone transmitter circuit 50 of Fig. 3 and are, 50 moreover, of the same frequency order as the telephonic waves produced in the circuit 50. Accordingly, the currents will reproduce at the receiver 102 the message impressed upon the transmitter arrangement.

55 The frequency of the current provided at the source 98 of the modulator 93 is in the case assumed of a value less than the frequency—33,000 cycles—of the current produced at the source 90 by an amount such as 60 to reproduce telephonic waves of an original frequency range from 200 to 3,000 cycles from inverted, telephonic waves ranging in frequency from zero to 2,800 cycles. If telephonic waves ranging in frequency 65 from 200 to 3,000 cycles per second were in-

verted in a frequency range different from zero to 2,800 cycles, the difference between the frequencies of the currents provided at the sources 90 and 98 respectively of the receiving arrangement of Fig. 4 must be correspondingly modified if it is desired to reproduce the telephonic waves in their original frequency range. Moreover, by suitably selecting the frequencies of the currents of the sources 90 and 98, the telephonic waves may, if desired, be reproduced in their original frequency order but at different frequency values or pitch, as will be clear from the discussion given above of the receiving system shown in Fig. 2.

70 When the system shown in Fig. 4 is employed to receive from a transmitting arrangement such as is shown in Fig. 3, the difference in frequencies of the currents at the sources 90 and 98 must be the same as the difference in frequencies of the currents at the sources 66 and 72 of Fig. 3 in order to reproduce the message at the same frequencies as those of the telephonic waves set up in the telephone transmitter circuit 75 50 of Fig. 3.

80 The receiving arrangement shown in Fig. 4 is not, however, restricted to use with the transmitting system shown in Fig. 3, but may also be utilized in receiving messages 85 from a transmitting arrangement of the kind shown in Fig. 1.

85 Detailed description of the modulators 14, 34, 60 and 84, the modulator-generators 24—26 and 54—56 and of the band filters 100 shown herein is deemed unnecessary because all of these devices may be and as shown are of well-known construction and constitute per se no part of the present invention.

90 While the invention has been described 105 as applied to a radio transmitting and receiving system; it is to be understood that the invention is equally applicable to other types of transmission, such as transmission over wires either by the carrier current 110 method or as direct transmission at the speech frequency level.

95 Having described my invention, what I claim is:

1. A method of secret, telephonic transmission, which includes producing telephonic waves, inverting the frequency order of said waves within a desired frequency range by converting them in inverted frequency order into a higher frequency range 115 and then stepping them down to the desired frequency range without affecting their inverted character, and transmitting a carrier wave modulated by the inverted, telephonic waves.

120 2. A method of secret, telephonic transmission which includes producing telephonic waves, inverting the frequency order of said waves by successive modulations of currents of frequencies different from each other and 125 130

- higher than the frequencies of the telephonic waves, suppressing the side band resulting from the last modulation which does not include waves corresponding to the telephonic waves in inverted frequency order, modulating a carrier wave by the inverted telephonic waves and transmitting the carrier wave.
3. A method of secret, telephonic transmission which includes producing telephonic waves, inverting the frequency order of said waves by causing them to modulate current of a higher frequency than the telephonic waves, suppressing the upper side band resulting from said modulation, modulating the lower side band by current of a frequency different from the above-mentioned, modulated frequency and also outside of the frequency range of the telephonic waves and suppressing the upper side band resulting from the last-mentioned modulation, modulating a high frequency carrier wave by the inverted, telephonic waves and transmitting the carrier wave.
4. A method of secret, telephonic transmission which includes producing telephonic waves, inverting the frequency order of said waves by causing them to modulate current of a superaudible frequency and causing the lower side band resulting from said modulation to modulate current of a second-superaudible frequency lower than the above-mentioned, modulated frequency by an amount determined by the desired value of the frequency range of the inverted, telephonic waves, modulating a carrier wave by the inverted waves and transmitting the carrier wave.
5. A method of secret, telephonic transmission which includes producing telephonic waves, inverting the frequency order of said waves within a desired frequency range by converting them in inverted frequency order into a high frequency range and then stepping them down to the desired frequency range without affecting their inverted character, transmitting a carrier wave modulated by the inverted, telephonic waves, producing from the carrier wave currents having the frequency characteristics of the inverted, telephonic waves, converting said currents into a higher frequency range and simultaneously inverting them to obtain currents of the frequency order of the original, telephonic waves, stepping down the frequency values of the last-mentioned currents substantially to those of the original, telephonic waves, and causing the resultant currents to operate an indicator.
6. A method of secret, telephonic transmission which includes producing telephonic waves, inverting the frequency order of said waves by successive modulations of currents of frequencies different from each other and higher than the frequencies of the telephonic waves, suppressing the side band resulting from the last modulation which does not include waves corresponding to the telephonic waves in inverted frequency order, modulating a carrier wave by the inverted telephonic waves, transmitting the carrier wave, producing from the carrier wave energy having the frequency characteristics of the inverted telephonic waves, successively modulating by said last-mentioned energy higher frequency currents differing in frequency by substantially the same amount as the difference between the frequencies of the first-mentioned currents to produce energy having the frequency characteristics of the telephonic waves, and causing said last-mentioned energy to operate an indicator.
7. A method of secret, telephonic transmission which includes producing telephonic waves, inverting the frequency order of said waves by causing them to modulate current of a higher frequency than the telephonic waves, suppressing the upper side band resulting from said modulation, modulating the lower side band by current of a frequency different from the above-mentioned, modulated frequency and also higher than the frequencies of the telephonic waves and suppressing the upper side band resulting from the last-mentioned modulation, modulating a high frequency carrier wave by the inverted, telephonic waves, transmitting the carrier wave, producing currents having the frequency characteristics of the inverted, telephonic waves, modulating by said energy current of the same frequency as the first-mentioned current, suppressing the upper side band resulting from said modulation, modulating the lower side band resulting therefrom by current of the same frequency as the second-mentioned current to produce energy having the frequency characteristics of the telephonic waves, and causing said last-mentioned energy to operate an indicator.
8. A method of receiving energy modulated by inverted, telephonic waves which consists in producing from the received energy currents having the frequency characteristics of the inverted, telephonic waves, converting said currents into a higher frequency range and simultaneously inverting them to obtain currents of the frequency order of the original, telephonic waves, stepping down the frequency values of the last-mentioned currents substantially to those of the original, telephonic waves, and causing the resultant currents to operate an indicator.
9. A secret, telephonic transmission system, including means for producing telephonic waves, two vacuum tube modulators for inverting the frequency order of said waves in successive steps, a filter interposed between said modulators, means for producing a high frequency carrier wave, means

for modulating the carrier wave by the inverted, telephonic waves and means for transmitting the carrier wave.

10. A secret, telephonic transmission system, including means for producing telephonic waves, means for inverting the frequency order of the telephonic waves and stepping them up to a higher range of frequencies, means for stepping down the inverted waves to a desired frequency level,

means for producing a carrier wave, means for modulating the carrier wave by the inverted telephonic waves and means for transmitting the carrier waves.

15. 11. A secret, telephonic transmission system, including means for producing telephonic waves, a modulator for inverting the frequency order of the telephonic waves and stepping them up to a higher range of

20 frequencies, a second modulator for stepping down the inverted waves to substantially the frequency level of the telephonic waves, means for producing a carrier wave, means for modulating the carrier wave by

25 the inverted telephonic waves and means for transmitting the carrier waves.

12. A secret, telephonic transmission system, including means for producing telephonic waves, a modulator for inverting the

30 frequency order of the telephonic waves and stepping them up to a higher range of frequencies, a second modulator for stepping down the inverted waves to substantially the frequency level of the telephonic

35 waves, means for producing a carrier wave, means for modulating the carrier wave by the inverted telephonic waves, means for transmitting the carrier waves, means including a vacuum tube detector for produc-

40 ing from the carrier wave energy of the frequencies of the inverted, telephonic waves, means for modulating by said last-mentioned energy current of the same frequency

45 as the modulated current in the first-mentioned modulator, means for modulating a side band resulting from the last-mentioned modulation by current of a frequency employed in the second-mentioned modulator, and an indicator operated by currents resulting from the last-mentioned modulation.

50 13. A receiver for energy modulated by inverted, telephonic waves comprising means for producing from the transmitted energy currents having the frequency characteristics of the inverted, telephonic waves, means

for converting said currents into a higher frequency range and simultaneously inverting them to obtain currents of the frequency order of the original, telephonic waves, means for stepping down the frequency values of the last-mentioned currents substantially to those of the original, telephonic waves and an indicator operable by the resultant currents.

14. A receiver for energy modulated by inverted, telephonic waves, including means for producing currents of frequencies equal and corresponding to those of the inverted, telephonic waves, means for modulating by

70 said last-mentioned currents current of a substantially higher frequency than the telephonic waves, means for modulating currents resulting from the first-mentioned modulation by current of a frequency dif-

75 fering from that of the first-mentioned, modulated current by an amount such as to produce currents having frequencies substantially equal to those of the original, telephonic waves, and an indicator connected

80 with the last-mentioned modulating means.

15. A receiver for energy modulated by inverted, telephonic waves including means for producing currents of frequencies corresponding to those of the inverted, telephonic waves, said means including a detector, means for modulating by said last-mentioned currents current of a super-audible frequency, means for modulating currents resulting from the first-mentioned modulation by current of a lower, super-audible frequency differing from the frequency of the first-mentioned, modulated current by an amount such as to produce currents having frequencies equal to those

90 of the original, telephonic waves, and an indicator connected with last-mentioned modulating means.

16. A receiver for energy modulated by inverted, telephonic waves including means for producing currents of frequencies corresponding to those of the inverted, telephonic waves, said means including a detector, two modulators connected with the output side of the detector in cascade relation with each other, means for supplying said modulators with currents of different, super-audible frequencies respectively, and an indicator connected with the second modulator.

ELLISON S. PURINGTON.
